US00D817304S

(12) **United States Design Patent** (10) **Patent No.:** **US D817,304 S**
(45) **Date of Patent:** **** May 8, 2018**

(54) **OVER EAR FUZZY EAR CUSHIONS AND ON EAR FUZZY EAR CUSHIONS FOR AUDIO HEADPHONES**

Primary Examiner — Paula Allen Greene

(74) *Attorney, Agent, or Firm* — Ward and Smith, P.A.

(71) Applicant: **Muzik, LLC**, Miami Beach, FL (US)

(57) **CLAIM**

(72) Inventor: **Jason Hardi**, Miami Beach, FL (US)

The ornamental design for over ear fuzzy ear cushions and on ear fuzzy ear cushions for audio headphones, shown and described.

(73) Assignee: **Muzik Inc.**, Raleigh, NC (US)

(**) Term: **15 Years**

(21) Appl. No.: **29/594,898**

(22) Filed: **Feb. 23, 2017**

(51) **LOC (11) Cl. 14-01**

(52) **U.S. Cl.**

USPC **D14/205**

(58) **Field of Classification Search**

FIG. 1 is an environmental perspective view of an over ear fuzzy ear cushions and on ear fuzzy ear cushions for audio headphones showing my design;

FIG. 2 is a front perspective view of an over ear fuzzy ear cushions and on ear fuzzy ear cushions for audio headphones showing my design;

FIG. 3 is a rear perspective view thereof;

FIG. 4 is a front view thereof;

FIG. 5 is a back view thereof opposite that of FIG. 4;

FIG. 6 is a left side view thereof;

FIG. 7 is a top view thereof;

FIG. 8 is an environmental rear perspective view thereof;

FIG. 9 is an environmental front view thereof;

FIG. 10 is an environmental side view thereof;

FIG. 11 is an environmental perspective view of an over ear fuzzy ear cushions and on ear fuzzy ear cushions for audio headphones showing my design;

FIG. 12 is a rear perspective view thereof;

FIG. 13 is a front view thereof;

FIG. 14 is a back view thereof opposite that of FIG. 4;

FIG. 15 is a left side view thereof;

FIG. 16 is a top view thereof;

FIG. 17 is an environmental rear perspective view thereof;

FIG. 18 is an environmental front view thereof; and,

FIG. 19 is an environmental side view thereof.

The broken lines depict environment that forms no part of the claimed design.
